UNITED STATES PATENT OFFICE.

JAMES B. MORGAN, OF DAVENPORT, IOWA.

DENTAL BRIDGEWORK.

SPECIFICATION forming part of Letters Patent No. 674,449, dated May 21, 1901.

Application filed June 12, 1900. Serial No. 20,050. (No model.)

To all whom it may concern:

Be it known that I, JAMES B. MORGAN, a citizen of the United States, residing at Davenport, in the county of Scott and State of Iowa, have invented certain new and useful improvements in Dental Bridgework; and I do hereby declare the following to be a full, clear, and exact description of the invention, such as will enable others skilled in the art to which it appertains to make and use the same.

The object is in bridgework to present a ready, simple, thoroughly-efficient, and durable means to secure false teeth in position against the gums and to permit a ready removal of such teeth for purposes of cleansing, &c.

The invention consists in the novel construction and combination of parts of a bridge system in dentistry, as will be fully described and claimed hereinafter.

In the accompanying drawings, forming a part of this specification, and in which like letters of reference indicate corresponding parts, I have illustrated a few of many ways of carrying my invention into effect, it being understood that I do not limit myself to the precise arrangement of parts herein shown.

In the drawings, Figure 1 is a view in plan of the keeper. Fig. 2 is a view in bottom plan of the anchor. Fig. 3 is a view in top plan of the same. Fig. 4 is a view in side elevation of the anchor. Fig. 5 is a view in plan, showing, diagrammatically, one-half of the roof of a human mouth, exhibiting the keeper in position upon two teeth. Fig. 6 is a view in top plan, exhibiting a plate to which the anchors are secured, the teeth being indicated in dotted lines. Fig. 7 is a view in side elevation, exhibiting the arrangements shown in Figs. 5 and 6, the false teeth being in position. Fig. 8 is a view in side elevation of a part of the upper jaw, exhibiting another manner of carrying my invention into effect. Fig. 9 is a view in side elevation, exhibiting still another manner of carrying my invention into effect. Fig. 10 is a view in plan, exhibiting the false teeth used in connection with the arrangement shown in Fig. 9, displaying the manner in which these teeth are held in place. Fig. 11 is a view in plan, exhibiting still another manner of carrying

my invention into effect in connection with the teeth of the lower jaw; and Fig. 12 is a view in elevation, exhibiting still another manner of carrying my invention into effect.

The gist of the invention resides in an anchoring device comprising a keeper A and an anchor B. The keeper, as exhibited in Fig. 1, comprises a band of metal having its back curved outward and provided with two inward-curved tongues or arms a. The anchor B comprises a plate b to engage the space between the back of the keeper and the arms a, and is curved, a cap b², (shown in Fig. 4,) and a loop or shank b³. Both of these parts, that is, to say, the keeper and the anchor, are preferably made of spring-gold when used in connection with gold crowns, and where used in connection with porcelain bridges the arms may be of spring-gold and the loop or shank of platinum.

The material in which the false tooth used is set may be porcelain, gold, silver, rubber, white-metal, or any of the usual materials used in dentistry for such purposes.

In carrying my invention into effect the keeper A is firmly soldered to the metal crown, as shown in Fig. 5, or may be soldered to a metal band a², as shown in Fig. 12. The anchor where used in connection with either a white-metal plate or with bridgework made of gold or other metal is soldered to or cast into such metal, with the arms extending beyond the plate a sufficient distance to engage the keepers, as shown in Fig. 6. Where the device is used in connection with rubber, celluloid, or the like, as shown in Fig. 11, the keeper, as usual, is soldered to the crown or to the band on the tooth and the anchor is embedded in the material carrying the false teeth.

As exhibiting the different positions in which my invention may be employed for securing various teeth in place, in Fig. 5 a gold crown is shown as securing a bicuspid and a molar, the keeper being soldered or otherwise secured, as by rivets, to the crown.

In Fig. 7, which is a side elevation of the arrangement shown in Fig. 5, the bicuspid and molar are clearly shown and the intermediate false teeth are preferably of porcelain, secured to the white-metal backing or plate shown in Fig. 8, it being understood

that this plate may also be made of gold or other metal, if preferred.

In Fig. 8 I have shown my invention as applied to two crowned teeth, one being a bicuspид and the other a molar, these two teeth carrying the keepers, and the intermediate false teeth, one a bicuspид and the other a molar, being of gold.

In Figs. 9 and 10 I have shown my invention as applied to four front teeth—that is to say, the four incisors. In this instance the front teeth are of porcelain and are secured to a rubber plate, to which latter are secured two arms b^4 of gold, carrying the anchors B. The keeper in this embodiment of my invention is shown as secured to the second bicuspид, which is covered by a gold crown, the crown either to inclose the tooth or to be secured to a root.

It is to be understood in all the embodiments of my invention that the crown may either inclose a tooth or may be secured to a root.

In Fig. 11 I have shown my invention as applied to the teeth of the lower jaw, in which the molars and one bicuspид on each side are false, the first bicuspид being provided with a crown carrying the keeper, and the false teeth being carried by an ordinary celluloid or vulcanized-rubber plate fitting the gum, as usual, the incisors and canine teeth being natural.

In Fig. 12 I have shown my invention as applied to a band secured around a tooth, the band to carry the keeper.

By the arrangements herein shown a firm and stable connection will be effected between the false teeth, carrying the anchor, and the crowned tooth or banded tooth, carrying the keeper, and as contact between the false tooth and the gum will be direct strain will practically be removed from the anchor-

ing device, so that to all intents and purposes the false tooth will be as sound and stable for all uses of mastication or the like as would be a natural tooth. By the arrangement shown 45 the false teeth may be disconnected from the natural teeth with readiness and ease and should the union between these parts at any time become loose it will only be necessary either to pinch in the arms of the keeper or 50 to straighten out the arms of the anchor, thus to take up any looseness that may result from long use.

Having thus fully described my invention, what I claim as new, and desire to secure by 55 Letters Patent of the United States, is—

1. An anchoring device for bridgework, comprising a two tongued or armed, curved keeper to be soldered or otherwise secured to a metal crown, or to a band on a natural tooth, 60 and an anchor having a two-armed head to engage the keeper, and a loop or shank to be firmly soldered to or embedded in the material to which the false teeth are or may be secured, substantially as described. 65

2. An anchoring device for bridgework, comprising a two tongued or armed, curved keeper to be soldered or otherwise secured to a metal crown, or to a band on a natural tooth, and an anchor having a two-armed head to 70 engage the keeper, a flanged cap on the head, and a loop or shank, together with the cap to be firmly soldered to or embedded in the material to which the false teeth are or may be secured, substantially as described. 75

In testimony whereof I affix my signature in the presence of two subscribing witnesses.

JAMES B. MORGAN.
